UNITED STATES PATENT OFFICE.

F. HUCKINS AND E. C. R. WALKER, OF ROXBURY, MASSACHUSETTS; SAID WALKER
ASSIGNOR TO SAID HUCKINS.

APPARATUS FOR DESICCATING AND TORREFYING FARINACEOUS SUBSTANCES.

Specification of Letters Patent No. 31,763, dated March 19, 1861.

To all whom it may concern:

Be it known that we, FRANCIS HUCKINS and E. C. R. WALKER, of Roxbury, in the county of Norfolk and State of Massachusetts, have invented a new and useful Improvement in Desiccating and Torrefying Farinaceous and other Substances; and we do hereby declare that the following is a full, clear, and exact description of the same, 10 reference being had to the annexed drawings, making a part of this specification, in which—

Figure 1, is a transverse vertical section of a means employed for carrying out our invention *x. x*, Fig. 2, indicates the plane of section. Fig. 2, is a longitudinal vertical section of the same taken in the line *y. y*. Fig. 1.

Similar letters of reference indicate corresponding parts in the two figures.

To enable those skilled in the art to fully understand and construct our invention we will proceed to describe it.

A represents a semi-cylindrical vessel of 25 cast metal and set directly over a furnace *B*, which may be of masonry. This furnace is indicated in red in both figures. Within the vessel *A*, there is fitted or placed a semi-cylindrical retort *C*, which is smaller than 30 the vessel *A*, so as to leave a space *a*, between them at all points. The retort *C*, is suspended within the vessel *A*, by flanches *b* which project from the ends and from both sides of the retort at its upper part, 35 the flanches resting in rabbets *c*, in the upper edges of the vessel *A*. On the upper part of the retort *C*, there is placed a semi-cylindrical top or cover *D*, which is perforated or has small tubes *d* fitted in it to allow the 40 escape of vapor from the retort.

The edges of the flanches *b*, *b* are grooved longitudinally or each has a V-shaped recess *e*, extending its whole length. The form of these grooves or recesses is shown 45 clearly in Fig. 1, and they admit of the retort *C*, being tilted at either side, the groove *e*, at one side catching on the upper edge of the rabbet *c* of the vessel *A* at the upper side as the retort is tilted. This will be 50 fully understood by referring to Fig. 1, in which the retort is shown in a tilted state in red. This tilting of the retort enables the contents to be removed therefrom with great

facility. The retort may be elevated at one side by any suitable hoisting device. 55

E, is a shaft which is placed longitudinally on the upper part of the retort and allowed to rotate freely in its bearings. On this shaft *E*, there are placed a series of arms *F*, in each of which a rod *f*, is fitted, said rods 60 having collars *g*, and spiral springs *h* on them. The springs *h*, have a tendency to keep the rods *f*, forced outward against stops *i*, at the ends of the arms *F*. At the ends of the rods *f*, there are placed scrapers 65 *j*, one on each end, the scrapers being simply bars of V-shape in their transverse section, and made to bear against the inner surface of the retort *C*, as they pass over it, by the springs *h*. The arms *F*, project from opposite sides of the shaft *E*, as shown clearly in 70 Fig. 2.

On one end of the shaft *E*, there is placed a pinion *k*, into which a toothed segment *l* gears. This segment is attached to the 75 front end of the vessel *A* and it has a vibrating movement given it by a crank *m*, and connecting rod *n*. On the shaft *E*, near each end of it, there is placed an arm or scraper *o*. These scrapers work over the 80 surfaces of the heads of the retort.

The operation is as follows:—The vessel *A*, is supplied with animal oil *p*, so that the retort *C*, will be in contact with it all around. The substance *G* to be desiccated or 85 torrefied is placed in the retort and heated through the medium of the oil *p*, the latter being heated by the furnace *B*. Oil as is well known boils at a temperature of 550° and consequently the substance in *C*, may 90 be subjected to a gentle or extreme degree of heat as circumstances may require and the heat to which the substance is subjected will be constant or uniform, and not subject to the quick fluctuations that it would 95 be were the retort *C*, over the fire chamber and heated directly from the fire. The substance *G* is stirred while being heated and having its moisture expelled from it, by rotating the crank *m*, which by means of 100 the rod *n*, communicates a vibratory or oscillating movement to the segment *l*, which in connection with the pinion *k*, on shaft *E*, give a reciprocating rotary movement to the shaft *E*, the latter making a complete 105 revolution in one direction and then in the

other. By this arrangement it will be seen that the substance G, may be stirred while within the retort C, and consequently without retarding in the least the desiccating or 5 torrefying process.

This invention has been practically tested in the manufacture of British gum and has been found to effect a great saving not only in fuel but also in labor and stock while the 10 quality of the manufactured article has been good. The stock or substance G, being prevented from burning and from being unduly heated.

Having thus described our invention, what we claim as new and desire to secure by Letters Patent, is:—

The employment in connection with the arms F and retort C of the self adjusting or spring scrapers j, constructed and operating as herein shown and described.

FRANCIS HUCKINS.
E. C. R. WALKER.
